UNITED STATES PATENT OFFICE.

THOMAS HUGHES DELABÈRE MAY, OF BATH, ENGLAND.

SACK-HOLDER.

1,237,936.

Specification of Letters Patent. Patented Aug. 21, 1917.

Application filed May 25, 1917. Serial No. 176,852.

To all whom it may concern:

Be it known that I, THOMAS HUGHES DELABÈRE MAY, M. A., A. R. S. M., a subject of the King of Great Britain, residing at Bath, in the county of Somerset and Kingdom of England, have invented certain new and useful Improvements in Sack-Holders, of which the following is a specification.

10 This invention relates to devices for holding open the mouths of sacks while these latter are being filled, weighing the said sacks if desired, and releasing the same when filled and placed on a cart, trolley or 15 the like, and the object of my invention is to effect an economy in time and labor required, only one person being required to do all the work, which with ordinary present day methods requires two or more persons, one for holding open the sack, and 20 the other for filling.

This device or holder can be suspended from any suitable projection such as the hook of a crane, or of a spring balance or 25 steel-yard, or if for field service the hook or tripod or movable stand on wheels or otherwise, with or without a steel-yard. The sacks while being filled are preferably entirely suspended from the holder but part 30 of the weight could rest on the ground or other support and part be counterweighted by a weight and cord over a pulley.

The device or holder consists of two complementary arms or levers pivoted to a common pivot or to a small bracket slidably mounted on a framework. This framework consists preferably of two parallel bars joined at top or bottom, so as to be either a single piece of steel, or joined up at each 40 end. Secondly, a clip sliding on the framework, and inclosing the continuations of the two arms, which for this purpose are bent to more than a right angle to a little beyond their pivot as shown. Thirdly, on the pivot 45 or bolt or bracket on which the two arms are pivoted is a clip for holding the back of the rim of the sack in a position somewhat higher than the working ends of the two levers when they are fully extended, so that 50 the mouth of the bag shall hang in a sloping position facing the filler.

Referring to the drawings:

Figure 1 is a front elevation, the arms or levers of the holder being shown fully extended.

Fig. 2 is a side view of Fig. 1.

Fig. 3 is a partial view showing the two

arms pivoted on independent pivots on a bracket.

In these 1 is the frame consisting in the device herein set forth of two parallel bars joined at the bottom. At the top between the two bars of the frame 1 is placed a hook 2 capable of rotating on a pivot 3, and of such shape that when in the position shown in Fig. 2, it forms a hook 4, and a locking surface 5, against which the gravity or spring lock 7 presses, and prevents it from moving. A stop 30 guides the hook to the stop in the right position for locking. Beneath this hook pivoted on a pivot 6 is a locking piece 7. This is weighted so that it naturally locks the hook in position but can be forcibly pulled out by hand when the hook having nothing to hold it flies up and liberates the apparatus. The frame 1 is shown somewhat bent at 8 so as to hold the hind bar 9 of the clip from sliding up or down the frame. This hind bar 9 of the clip and the front bar 10 are held in position by a nut and bolt 11, and control the upper parts 12 and 13 of the arms which fit in between the two bars of the clip. These two bars are kept the right distance apart by distance pieces with or without anti-friction rollers 31 on the studs or bolts 32. The anti friction rollers therefore allow the parts 12 and 13 to move on them without much friction. The arms 12 and 13 with their lower parts 14 and 15 are pivoted together on the bolt 16 which slides freely in the slot of framework 1. On this bolt 16 is also attached hook 18 so as to hang freely. This hook has pivoted to it by the pivot 19 a clamp rod 20, and also at 21 there is pivoted to it a second clamp piece 22. The clamp rod 20 has a tail end 23 abutting against the tail end 24 of the other clamping piece 22. The lower parts 14 and 15 of the arms are bent forward a little, and preferably are twisted near the ends. Each preferably carries a friction pulley 25 fastened to it by a pivot 26 to cause it to slip easily on the inside of the sack as the sack descends and is strained open. The mode of action is as follows:— The hook 4 being clamped as shown in Fig. 2 by the locking piece 7 it is suspended on the scale beam or on a sling or other hook, and the lower arms somewhat separated. The back portion of the sack is placed on the clamp piece 20 pressing it outward. This presses the tail inward, which again presses the tail of piece 22,

110

the upper part of which clamps the bag firmly between the projecting face of clamp 20 and itself. The lower parts of the arms are now placed inside the sack and spread out wide as they descend by gravity in the frame until they thoroughly hold the sack. The upper parts of the arms rise up and being held by the anti-friction rollers 31, with a little assistance by the operator the 10 weight of the holder, sack and contents depress by their gravity the pivot 16 in the slot as far as the arms pressing against the sack will allow it to go. The moment however the sack is filled, and is liberated to 15 rest on the truck or the like, the pivot 16 is free to rise, and the lower parts of the arms fall naturally inward until they lie nearly or quite one against the other and the sack is liberated. The apparatus is 20 now hooked up in place again, and is ready for use with another sack. When the bag is placed in position on the arms, and the clamp, the weight coming on the clamp mainly, the bag is suspended, and can be 25 filled at leisure. It can be weighed while on the steel yard, can be hoisted up by any mechanism, and placed on a truck or the like, and then the lock 7 turned over when the hook 4 is free to rotate and it is unhooked 30 from its support. It is now found that the two arms fold back toward each other, and they can be readily taken out of the sack, and there being no longer any weight 35 on the back part of the rim of the sack, it is immediately freed from clip 20, 22.

It will be obvious in this description that the distance between the bottom of the slot or space in the framework, and the clamp 9 must be only such as will not allow the very 40 ends of the upper parts of the levers 12 and 13 to escape through the clamp 9, 10.

In Fig. 3, I simply show a small modification in which the two arms 12, 14, 13 and 15 respectively are separately pivoted on 45 two pivots 16 and 27. By this arrangement the arms do not cross each other, and consequently the width between the two clamping pieces 9 and 10 can be only half the width shown in Figs. 1 and 2.

50 I declare that what I claim is:—

1. A sack holder comprising a vertical frame, a vertically freely movable slide

mounted on the frame, two sack-holding arms pivoted between their ends to said slide and having their upper ends bent outwardly 55 in opposite directions, and relatively fixed operating means on the frame above the slide and engaging said bent ends to positively force them together and move the lower sack-engaging ends outwardly as the 60 slide is moved downwardly by the weight of the filled sack.

2. A sack holder comprising a vertical frame, a vertically freely movable slide mounted on the frame and provided with a 65 sack-engaging device, two sack-holding arms pivoted between their ends to the slide and having their upper ends bent outwardly in opposite directions, and relatively fixed operating means on the frame above the 70 slide and engaging said bent ends to positively force them together and move the the lower sack-engaging ends outwardly as the slide is moved downwardly by the weight of the filled sack.

75 3. A sack holder comprising a vertical suspension frame, a vertically freely movable slide on the frame, a stationary loop mounted on the frame above said slide, a sack clamp mounted on the slide, two sack-engaging arms pivoted by a common pivot to the slide with their upper crossed ends 80 extending freely through said loop for positive action thereby.

4. A sack holder comprising a vertical 85 suspension frame, a vertically freely movable slide mounted on the frame, a hook depending from the slide, two interengaging clamp rods pivoted to said hook, two crossed sack-engaging arms pivoted to said 90 slide and having their upper ends bent outwardly in opposite directions, and relatively fixed operating means on the frame above said slide and engaged by the outer edges of the outwardly bent ends of said crossed 95 arms for the purpose stated.

In witness whereof, I have hereunto signed my name this first day of June, 1917, in the presence of two subscribing witnesses.

THOMAS HUGHES DELABÈRE MAY.
